SANDS-DISCHARGE VALVE

Harry A. Linch, Westport, Conn., assignor to The
Dorr Company, New York, N. Y., a corporation
of Delaware

Application May 16, 1942, Serial No. 443,317

4 Claims. (Cl. 209—491)

The invention relates to sands-discharge valves having particular adaptation for use in hydraulic classifiers of the hindered-settling automatic-control type.

An apparatus for which the invention has been devised and is particularly applicable is the form of classifier commonly known as "Fahrenwald sizer." The form of such apparatus is shown and described in British Patent No. 268,663 the acceptance date of which was April 7, 1927, and also in Bulletin No. 2381 copyrighted in 1928 by The Dorr Company, which bulletin is entitled "The Fahrenwald Sizer."

An apparatus of the general class to which the invention hereof has particular application comprises a tank structure providing in the upper portion thereof a relatively long settling chamber or zone, classifying pockets or zones in constant direct communication with and extending downwardly from the settling chamber, and pressure compartments underlying the classifying pockets but functionally-separated from the latter by apertured constriction plates defining the bottom of the classifying pockets or zones on the one hand and the roof or top portions of the pressure compartments on the other hand. Such apparatus has an hydraulic header connected for supplying water under pressure to the pressure compartments from which the hydraulic water passes forcibly upwardly through the apertures of the constriction plates into the bodies of material in the classifying pockets. Such apparatus is also equipped with sands-discharge means that includes sands-transfer tubes leading downwardly from the lower portion of the classifying pockets to the exterior of the apparatus and associated valve constructions of which the movable valve elements have mechanisms for automatically lifting the valves from their seats to release from said pockets through said transfer tubes, according to operative requirements, quantities of the sands accumulated in the pockets.

An object of the present invention is to provide a valve-discharge construction or arrangement which is effective and more readily and more conveniently adjustable than any type of valve construction which has heretofore been used in such apparatus.

As illustrative of a specific manner by which the new valve construction hereof is realized and the manner in which it is employed, reference is made to the accompanying drawings constituting a part of this specification.

In said drawings:

Figs. 1 and 2 are respectively views showing in

5 plan and in side elevation a hindered-settling apparatus of the type to which the new valve construction has particular application. In Fig. 2 a portion of a side plate is broken away to disclose certain interior features of construction.

10 Fig. 3 is a vertical longitudinal view of which the tank or casing structure is shown as a sectional view taken as on the vertical plane indicated by the line 3—3 of Fig. 1 looking in the direction of the arrows.

15 Fig. 4 is a vertical transverse sectional view taken as on the vertical plane indicated by the line 4—4 of Fig. 1 looking in the direction of the arrows. In this view the valve construction is clearly shown as to the details thereof.

20 Reference is now made to the drawings in detail wherein like reference characters refer to like parts throughout the several views.

25 The hindered settling apparatus illustrated has a tank structure generally designated as 10, which in plan provides a progressively expanding area in basin from the feed-receiving end 11 thereof to the wider overflow end 12 thereof. The tank structure 10 includes rear side walls 13, a narrow feed-receiving end wall 14 that includes the sections 15, 16 and 17 and a wide overflow end wall 18 having a vertically adjustable upper overflow edge plate or member 19 that is secured in adjusted position by bolts 20. The tank structure also includes an outside structure providing an overflow receiving launder that includes vertically-extending end members 21, 21, vertically-extending side members 22, 22 and inclined floor plates or launder bottoms 23. The launder has a discharge area at the lower end thereof provided at 24. There is a transverse plate member 25 outwardly disposed with respect to the overflow plate 19. This member 25 extends between the side walls 13 and with a horizontally-extending transverse plate 26 provides a receiving pocket 27 for receiving liquid or fines overflowing said plate member 19. Rising small side members 28, 28 complete an outflow trough 29 leading from the compartment 27. The interior of the tank is divided by vertically-extending partitions or plates 29 into compartments 30, 31, 32, 33, 34, 35 and 36. These partitions extend upwardly within the tank for a major portion of the height thereof and for each of these compartments or sub-sections of the tank there is provided an apertured flow constriction plate 37. As to compartment 30 the constriction plate for this compartment is at an elevation only a slight distance below the top edge of the transverse partition 29 and this particular plate is located at and

defines the lowermost portion of the feed-receiving section 11 of the classifier. Below the constriction plate for compartment 30 there is a pressure compartment 41. As to each of the other compartments the constriction plate 37 defines the floor of a classifying pocket or zone 38 and the roof or upper limits of a hydraulic pressure chamber or compartment 39. The tank is provided with means generally designated as 40 for supplying water under pressure to the compartments 39 and to the compartment 41. The means 40 just referred to includes a supply tank 42 for holding liquid therein up to a relatively constant surface elevation and pressure water passes from this tank through a descending pipe 43, controlled by a stop valve 44 and a horizontally-extending hydraulic header 45 from which the pressure liquid is supplied to the several pressure compartments as 39 and 41 as through the medium of branch pipes 46. In the construction shown these branch pipes are realized by short sections of flexible tubing the area through which can be adjusted by clamping straps 47 whereby these branch pipes are in effect provided with a valve construction because of these clamping members 47 which can be relied upon to adjust the flow area through the respective branches. The flexible branch tubes 46 are secured in place as by clamps 48 whereby liquid-tight joints are provided because of such clamps. Sands-discharge tubes 49 are provided for and lead from each of the compartments 38 to the exterior of the tank. These sands-discharge tubes 49 extend, as will be seen from an inspection of Fig. 4, through and from the upper side of the constriction plate 37 and have a watertight connection with the latter through the medium of the securing rings 50 and 51. Window structures are provided at 52 whereby operating conditions within the interior of the classifying pockets can be readily observed by the operator. For the wider and latter functioning portions of the apparatus the side walls 13 are cut out as at 53 and 54 and these side walls are equipped with adjustable overflow plates 55 or 56, as the case may be, which are positioned according to general surface level of the liquid within the tank 10 and for attaining the desired type of overflow from the respective sections of the tank served thereby. These overflow plates or members are secured in adjustable position as by bolts 57.

The valve structure which constitutes the basis for this invention is shown in Fig. 4 at a somewhat larger scale than in the other figures. It embodies a vertically-extending tubular main member 58 frequently referred to as the tubular valve support. This tubular valve has openings or windows 59 at the lower portion thereof providing that which is sometimes referred to as sands-transfer passageways or area leading from the exterior to the interior of the tubular support. The lower end portions 60 of this member 58 are connected as by welding to a horizontally-extending centrally apertured member 61 the underside of which is counter-bored at 62 for receiving therein a circular centrally apertured valve seat 63. A lower clamping member or valve bushing 64 is provided for engaging the underside of the valve seat and screws 65 are employed for drawing the valve bushing 64 towards the valve seat receiving member 61 whereby the members 61 and 64 cooperatively secure the valve seat in position therefor. This valve seat 63 is preferably made of rubber or some

yieldable composition. It is feasible, however, to make it of steel and as it extends horizontally it, with the members 61 and 64, provide a down-flow passageway leading from the tubular member 58 when downwardly tapering valve 66 is raised from seat-engaging position therefor. This valve normally rests upon the seat as shown in Fig. 4 but the structure that controls the operation of the valve automatically lifts the valve from the seat as and when there is a sufficient accumulation of sands within the pocket, particularly to a region above that of the openings 59 that are provided at the lower end of the tube 58. A horizontally-extending member is secured to the upper end of the tubular valve support 58 so as to provide a liquid-tight cover or cap 67 therefor. This cap has a vertical screw-threaded opening 68 extending therethrough for receiving an exteriorly-threaded tubular member 69 which is sometimes referred to as a tubular valve sleeve. A relatively tight fit is provided for the screw-threaded portions just referred to and a locking nut 70 may be employed whereby a relatively liquid-tight joint is attained as between the screw-threaded opening 68 on the one hand and the exteriorly-threaded member 69 on the other hand. This tubular valve stem member 69 has a dish-shaped member 71 connected to the upper end so as to provide a liquid-tight connection at this point. As shown this member 71 is in the form of the surface section of an inverted truncated cone. It has a marginal flange portion 72. This dish-shaped member 71 is sometimes referred to as the diaphragm chamber or diaphragm chamber structure. A flexible diaphragm 73, preferably of rubber but which may be of any other suitable yieldable and flexible material impervious to the passage of water, is secured as by bolts 74 to the marginal portion 72 of the diaphragm chamber structure 71. When the valve 66 is in normal closing position with respect to the seat 63, the diaphragm 73 has a shallow dish-shaped appearance; it preferably takes the form of the surface of an inverted truncated portion 45 of a shallow cone. At the underside of the diaphragm and in direct contact therewith, there is a clamping washer 75 of relatively small diameter and immediately above the diaphragm there is a dish-shaped washer 76 of relatively 50 large diameter. The larger washer 76 is dish-shaped so as to substantially fit the upper contour or surface of the central section of the diaphragm when the parts are in the normal position shown in Fig. 4. An upper vertically-extending tubular member 77 which is exteriorly threaded at the lower end 78 thereof extends through the diaphragm and upper and lower locking nuts 79 and 80 serve to engage and press the washers whereby they in turn clamp the central portions of the diaphragm in a manner to effect a liquid-tight joint as between the diaphragm on the one hand and the upper tubular member 77 on the other hand. This member 77 is sometimes referred to herein as the tubular 60 valve stem guide since it receives and has passing upwardly therethrough a valve stem 81 the lower end 82 of which is rigidly connected to the tapering valve plug or movable valve element 66. This stem 61 as will be manifest from the drawings extends upwardly through the tubular valve support 58, the tubular valve sleeve 69 and the tubular valve stem guide 77 and upwardly beyond the latter a sufficient distance to provide the threaded end 83 having thereupon an adjusting 65 wing nut or valve-rod positioned member 84.

The threaded end 83 also carries removable and replaceable weights 85 which may be clamped in position on the rod by the means of clamping nuts 86 and 87.

Means is provided for supplying pressure water at relatively constant pressure head to the upper interior portion of the tubular valve support 58. This means includes a branch pipe 88 leading from the downwardly-extending main pipe 43, an adjustable valve 89, a horizontal pipe section 90 from which there upwardly extends overflow piping that includes a riser pipe 91, a T connection 92 with an overflow branch 93 having downwardly-extending release pipes 94 and 95 and 96 for passing overflowed liquid from the overflow T 92 into the feed-receiving section 11 of the tank. Subsequent portions of the horizontally-extending pipe 90 have branch pipes 97 leading therefrom and connected at 98 to the upper portion of the tubular valve supports 58 whereby liquid from this constant pressure supply line 90 can be transferred to and delivered directly into the upper interior portions of the tubular valve supports 58. An air-release passageway is provided at 99 leading from the upper interior portion of the member 58. In the construction shown an air-release pipe 100 is indicated extending from this release opening 99 of elevation and preferably terminating at an elevation somewhat higher than that of the upper tubular valve stem guide 17. This pipe 100 may be equipped with a valve 101 and if so equipped the portion above the valve could be omitted as the valve would normally be closed to retain the pressure within the tubular support 58 in so far as the escape of air or water from the release opening 99 is involved. In that instance the valve 101 would be opened merely to permit the escape of air which might otherwise become entrapped within the tubular support 58. By the same token one will readily appreciate the fact that this release opening 99 might be provided only with a threaded plug which would normally close it, but which could be removed for permitting the escape of air which might otherwise become entrapped in undue quantities within the tubular support 58. This air discharge passageway 99 and whatever instrumentality is employed in conjunction therewith to control or permit the release of air may be referred to as means for releasing entrapped air. Said means can be relied upon and employed for ensuring a retention of pressure liquid within the tubular valve support up to that which may be realized incident to the feeding of pressure water into the upper interior portion of the tubular support through the inflow opening 98 therein.

In the normal functioning of the apparatus solid material to be sized or separated is supplied to the feed receiving end of the apparatus. As the operative steps are carried out certain fines pass as overflow along one path after the classifying operation while sands graded as to size pass along other paths as the classifying operations are carried out. During the classifying operations the sands are initially subjected to the upflow currents of pressure water received within the compartment 39. Afterwards the water and sands gradually pass along the machine whereby they are progressively treated therein. The sands are subjected to the upflow currents in the classifying pockets of progressively increasing horizontal area. The heavier sands settle in the first classifying compartment; sands of less weight but still heavy settle in the second classi-

fying compartment and finally sands which have not been separated and settled in the preceding compartment are ultimately received in the last of the compartments indicated. In each of the classifying pockets hydraulic water passes from the pressure compartment corresponding thereto upwardly through the apertures of the constriction plate 31. The greatest velocity of upflow is in the compartment of smaller horizontal cross-sectional area and there is a decrease of velocity of flow for the successive larger classifying pockets. The sands settle and progressively accumulate in each of the compartments. They gradually build up about the lower ends of the tubular valve supports 58 until they extend substantially above the tops of the openings 59 in the valve support corresponding thereto. Until such building up of sand is realized there is a release through the passageways 59 of pressure liquid that was received in the upper portion of the tubular portion 58. However, when this escape for such water is cut off due to the sands accumulation within any particular compartment then the pressure of the liquid received within the tubular valve support 58 becomes effective upwardly through the tubular valve sleeve 69 and within the diaphragm chamber structure 71 whereby it causes a rising of the diaphragm and a consequent lifting of the valve 66 from seating position. This allows an outflow of liquid and sand from any particular compartment 38 and a consequent passing of sands by the valve plug through the seat 63 and from the apparatus through the medium of the descending sands-transfer pipe 49. This condition continues until there has been sufficient discharge of sands from the particular compartment whereby there can follow an outflow of pressure valve-operating liquid from the interior of the vertically-extending tubular support 58 and a consequent release of pressure at the underside of the diaphragm. This allows the diaphragm to return to normal position, or as otherwise expressed, to normal valve seating position for the valve element or plug 66. As to the diaphragm it will be noted that as that tends to raise it initially exerts full pressure against the underside of the upper dish-shaped washer 76. However, as the central portion of the diaphragm continues to rise there is first a separation of the outer marginal portion of the washer 76 from the diaphragm due to the change in shape of the diaphragm and if the diaphragm reaches the full extent of upward movement therefor, there will ultimately be contact between only the small central portion of the washer 76 with the small central portion of the diaphragm itself and there will be an area between them which in vertical cross-section is in the form of a V. From the foregoing it will be noted that considerable agitation exists within the classifying pockets of the tank and extends, to a certain degree, into a region somewhat above the upper portions of partitions 29. This agitative effect which is produced because of pressure-liquid that is upwardly delivered through apertures of the constriction plate becomes considerably dissipated within the classifying compartment or pockets 31, 32, etc. so that little, if any, agitation exists within the upper portions of the pockets, this because the energy of the upflowing water has been used up or absorbed by the sands undergoing hindered settling in the lower portion of the classifying compartment. The agitative effects are therefore substantially dissipated within at least a short

region above the top of the classifying compartments and there is realized a relatively large open bottom settling compartment or zone overlying the pockets and extending substantially throughout the entire upper interior portion of the tank and it is from the upper portion of this settling zone that the finer material passes as overflow over weirs or overflow edges such as provided by plates 55, 56 and 19.

What is claimed is:

1. A sands-discharge valve construction comprising a vertically-extending main tubular member; means providing a movable valve and seat therefor; a cover at the upper end of the main tubular member having a vertically-extending sleeve-receiving opening therethrough; a vertically-positionable tubular sleeve extending through the opening and having a substantially water-tight connection with the cover, chambered means providing an expandable and contractible compartment having a lower member connected to the upper end of the tubular sleeve and an upper member providing a vertically-movable element; a depending valve-positioning member carried from the vertically-movable element and extending to the valve downwardly within the chambered means, the tubular sleeve and the main tubular member; said construction being characterized in that it includes a liquid-transfer pipe leading into the upper portion of the main tubular member for supplying pressure water thereinto whereby the pressure of the water thus supplied ultimately becomes effective on the vertically-movable element of the chambered means through the medium of the vertically-positionable tubular sleeve, an air release means providing a passageway leading from the upper interior portion of the main tubular member and means for at will closing or opening said passageway.

2. A sands-discharge valve construction comprising a vertically-extending main tubular member; means providing a movable valve and seat therefor; a cover at the upper end of the main tubular member having a vertically-extending sleeve-receiving opening therethrough; a vertically-positionable tubular sleeve extending through the opening and having a substantially water-tight connection with the cover, chambered means providing an expandable and contractible compartment having a lower member connected to the upper end of the tubular sleeve and an upper member providing a vertically-movable element; a depending valve-positioning member carried from the vertically-movable element and extending to the valve downwardly within the chambered means, the tubular sleeve and the main tubular member; said construction being characterized in that it includes a liquid-transfer pipe leading into the upper portion of the main tubular member for supplying pressure water thereinto whereby the pressure of the water thus supplied ultimately becomes effective on the vertically-movable element of the chambered means through the medium of the vertically-positionable tubular sleeve, a pipe leading from the upper interior portion of the main tubular member and rising to an elevation higher than that of the chambered means, and a valve positionable for

opening or closing of the passageway through said pipe.

3. A sands-discharge valve construction comprising tubular means that includes a vertically-extending main tubular member at the lower end of which there is a sands-transfer area leading from the exterior to the interior thereof and a tubular sleeve vertically-positionable with respect to the main tubular member; means providing a movable valve and an apertured seat therefor near the lower end of the main tubular member; chambered means providing an expandable and contractible compartment having a lower member carried by, connected to, and in communication with the upper end of the tubular sleeve and an upper member providing an upper yieldable element; and means carried from said vertical yieldable element for positioning said valve relative to its seat; said construction being characterized in that it includes water supply means for delivering pressure water into the vertically-extending main tubular member and having a supply water overflow at elevation higher than that of the upper member of the chambered means, and in that there is a pipe leading upwardly from the interior of the main tubular member to an elevation higher than that of the supply water overflow.

4. A sands-discharge valve construction comprising a vertically-extending main tubular member; means providing a movable valve and seat therefor; a cover at the upper end of the main tubular member having a vertically-extending screw-threaded sleeve-receiving opening therethrough; a tubular sleeve extending through the opening and having an exteriorly screw-threaded portion turnably fitting and engaging the internal screw-threads of the sleeve-receiving opening of the cover thereby affording in conjunction with said internal screw-threads a means whereby the tubular sleeve can be vertically adjusted by horizontally turning said sleeve about a vertically-extending axis, chambered means providing an expandable and contractible compartment having an upper member providing a vertically-movable element and having a lower member connected to the upper end of the tubular sleeve whereby said chambered means is carried by and turns with said tubular sleeve; a depending valve-positioning member carried from the vertically-movable element and extending to the valve downwardly within the chambered means, the tubular sleeve and the main tubular member; said construction being characterized in that it includes a liquid-transfer pipe leading into the upper portion of the main tubular member for supplying pressure water thereinto whereby the pressure of the water thus supplied ultimately becomes effective on the vertically-movable element of the chambered means through the medium of the vertically-positionable tubular sleeve and wherein said vertical adjustment of the exteriorly-threaded sleeve and of the aforementioned chambered means can be accomplished by turning the tubular sleeve and this while the liquid transfer pipe continues to be connected for supplying water to the interior of the main tubular member.
